LAMP BASE

Lee Sechrist, Euclid, Ohio, assignor to Phil-Mar Corporation, Cleveland, Ohio, a corporation of Ohio

Application June 28, 1950, Serial No. 10,793

Term of patent 3½ years

(Cl. 48—20)

To all whom it may concern:

Be it known that I, Lee Sechrist, a citizen of the United States and a resident of the city of Euclid, county of Cuyahoga, and State of Ohio, have invented a new, original, and ornamental Design for a Lamp Base, of which the following is a specification, reference being had to the accompanying drawing, forming a part hereof.

The socket and harp supported by the lamp base are shown in broken outline for the purpose of illustration only.

I claim:

The ornamental design for a lamp base, substantially as shown and described.

LEE SECHRIST.
